UNITED STATES PATENT OFFICE.

THOMAS M. FISHER, OF BASTROP, TEXAS.

CATTLE-GUARD.

1,320,217.

Specification of Letters Patent.

Patented Oct. 28, 1919.

Application filed February 1, 1919. Serial No. 274,433.

To all whom it may concern:

Be it known that I, THOMAS M. FISHER, a citizen of the United States, and a resident of Bastrop, in the county of Bastrop and State of Texas, have invented certain new and useful Improvements in Cattle-Guards, of which the following is a specification.

My invention is an improvement in cattle guards, and has for its object to provide a device of the character specified, formed from sheet metal sections adapted to be arranged between the rails and on the outer sides of the rails to prevent the passage of stock.

15 In the drawings:

Figure 1 is a perspective view of the improved guard;

Fig. 2 is a top plan view;

Fig. 3 is a longitudinal vertical section; 20 Fig. 4 is a transverse vertical section.

The present embodiment of the invention is shown in connection with a section of railway track composed of the usual rails 1 and cross ties 2 and 3. The improved guard, 25 which is formed of sheet metal, consists of three sections, namely, a section adapted to fit between the rails and a section adapted to be arranged at the outside of each rail, and of a width to extend from the rail to 30 beyond the end of the tie.

The sections are similar in construction, each being formed from a sheet of metal of suitable size bent in zigzag form to provide a series of steps, that is, a series of substantially vertical surfaces 4 and inclined surfaces 5 connecting the vertical surfaces. 35 The surfaces 4 are parallel with each other, as are also the surfaces 5, and before bending the sheet a series of tongues 6 is formed.

40 Each tongue is formed by slitting the sheet on converging lines, and these tongues are arranged in series, a series extending in the same plane with each surface 5. The tongues being formed, that is, being slit, before the metal is bent, it will be obvious that the tongues of each surface 5 will be 45 spaced above the adjacent surface 5 a distance corresponding to the width of the surface 4. The tongues in the successive series 50 are in staggered relation, as clearly shown.

Since the surfaces 5 are parallel, and since

the surfaces are inclined, when the surfaces 4 are arranged vertically as shown in Fig. 3, the tongues 6 will incline upwardly at an angle to the plane of the track, as shown in 55 Fig. 3. Preferably, the free ends of the tongues are bent slightly, as indicated at 7, so that the upper faces of the tongues at their highest parts are below the level of the tread of the rail.

60 That portion of the track which is to receive the sections is formed from ties which are arranged with their wide dimension vertical, and the intermediate ties of the series which will support the guard have one corner beveled, as shown at 8. The ties are arranged with these beveled corners upward and similarly arranged, and the bevel corresponds to the incline of the surfaces 5. When the sections are laid upon the ties so 70 formed, it will be obvious that the surfaces 5 will rest upon the inclined tops of the ties while the surfaces 4 will engage the vertical faces of the ties.

75 At each side each section has a surface 9 which is perpendicular to the surfaces 4, and these surfaces 9 rest upon the endmost ties in the series which are not beveled. These surfaces have openings for receiving spikes 10 to secure the sections to the ties. 80 The upwardly extending pointed tongues will deter any stock that might be tempted to cross the guard.

I claim:

85 A cattle guard comprising a sheet metal plate having stamped therefrom tongues arranged in rows with the tongues in each row staggered in relation to those in the next successive row, all of said tongues being similar and facing in the same direction, said plate being bent transversely to provide alternate vertical and inclined portions engageable against the cross-ties of a railroad track, said tongues extending as continuations of said inclined portions and being 90 downwardly curved whereby their end portions will be substantially horizontal, and securing flanges on said plate.

95 THOMAS M. FISHER.

Witnesses:

TIGNAL JONES,

E. KIMICHS.
